UNITED STATES PATENT OFFICE

CLIFFORD NORTON, OF ORANGE, AND NEVILLE S. DICKINSON, OF GLEN RIDGE, NEW JERSEY, AND JOHN G. GUSTAFSON, OF NEW YORK, N. Y., ASSIGNEES TO ELEVATOR SUPPLIES COMPANY, INC., OF HOBOKEN, NEW JERSEY, A CORPORATION OF NEW JERSEY.

DOOR-OPERATING MECHANISM FOR ELEVATORS

Application filed October 11, 1921. Serial No. 508,359.

This invention relates to elevators and, more particularly, to door or gate operating and controlling mechanisms therefor. A general object of the invention is to provide an improved and simplified mechanism for operating the door of an elevator by power and for controlling the operation of the same.

Elevators have heretofore been provided with mechanism for operating the doors by power which is so controlled that the door operating mechanism is thrown into operation automatically when the car is stopped at any one of the floors which the elevators serve. Door operating mechanisms of this latter type have been rather complicated in construction and operation and expensive to manufacture, and another object of the invention is to simplify and improve the construction of door operating mechanisms of this type.

With the above and other objects in view, the invention involves certain novel and improved features, constructions and combinations of parts hereinafter described and particularly pointed out in the claims. Certain of these features enable the amount of mechanism provided for the actuation and control of the doors to be greatly reduced and the construction and operation thereof considerably simplified as compared with prior constructions. In the present embodiment of the invention, a door operating line is provided for operating all of the doors and means is provided for connecting any one of the doors with the line for movement therewith and certain features of the invention relate particularly to the mechanism for connecting the doors with said line and the means for controlling said mechanism. Certain features of the invention relate to improvements in the mechanism for controlling the selective operation of the doors by the door operating mechanism.

The invention will be readily understood from the accompanying drawings illustrating an elevator mechanism embodying the invention in its preferred form and the fol-

lowing detailed description of the constructions therein shown:

In the drawings:

Fig. 1 is a view in vertical section of an elevator hatchway with the central part thereof broken away so that only one floor is shown;

Fig. 2 is a view in horizontal section illustrating particularly the mechanism in the penthouse at the top of the hatchway;

Fig. 3 is a detail view in side elevation illustrating particularly the gate or door operating mechanism;

Fig. 4 is a view partly in front elevation and partly in section, illustrating a portion of the mechanism shown in Fig. 3;

Fig. 5 is a plan view of the mechanism shown in Fig. 3;

Fig. 6 is a view in vertical section illustrating a portion of the hatchway of an elevator serving three floors;

Fig. 7 is a view in side elevation illustrating in modified form certain parts of the gate or door operating mechanism;

Fig. 8 is a plan view of the mechanism shown in Fig. 7;

Fig. 9 is a view in front elevation of a portion of a door to which certain parts of the mechanism shown in Figs. 7 and 8 are attached;

Fig. 10 is a wiring diagram of the elevator mechanism and Fig. 11 is a diagrammatic view illustrating the mode of operation of the knock-out device.

In the drawings is illustrated an elevator hatchway in which runs a car indicated at 1, serving three floors although the elevator mechanism may readily be varied to suit the requirements for any number of floors. The car hoisting mechanism comprises a cable 2 attached to the car and passing about a hoisting drum 4 located in the penthouse. The hoisting drum is driven during the normal running of the elevator through a belt 6 from a main hoisting motor 8. The present invention may be embodied in an elevator mechanism in which the stopping of the car is controlled by an automatic floor controller.

driven through suitable connections from the hoisting mechanism or in an elevator mechanism in which the starting and stopping of the car is controlled by a hand controller. As illustrated in the drawings, the current through the hoisting motor 8 is controlled by means of a sliding controller 10, and the direction of the current through the motor is controlled by reversing switches 10 12 and 14.

The electrical connections for controlling the starting and stopping of the elevator are clearly shown diagrammatically in Fig. 10. In the diagram illustrated in this figure, 16 and 18 indicate the main circuit leads. As shown in this figure, the circuit through the motor has been closed by the controller 10 and the positions of the reversing switches 12 and 14 are such that the motor 8 is rotated 20 in a direction to elevate the car. With the reversing switches in this position, a circuit may be traced from the lead 16 through the wire 19, master interlock switch 20, wire 21, contact 22, reversing switch 12, wire 24, controller 10, resistance 26, wire 28, through the hoisting motor 8 and from the hoisting motor through the wires 30 and 32, the reversing switch 14, contact 34 and wires 35 and 36, back to the other side 18 of the line. 30 From the controller 10 a shunt circuit is made through the contact 37 and through the magnet or solenoid 38 across to the wire 30 at the point 39. In reversing the motor, the reversing switches 14 and 12 are shifted to 35 carry the reversing switch 14 from engagement with the contact 34 into engagement with the contact 22 and to carry the reversing switch 12 from engagement with the contact 22 into engagement with the contact 40. 40 When the motor is cut out, the controller 10 is located at the left of the position in which it is shown in Fig. 10, so that the motor circuit is broken between the controller and the resistance 26 and the circuit for the 45 solenoid 38 is broken between the controller and contact 37. In starting the motor, the controller 10 is shifted to the right thereby establishing an electrical connection between the controller and the resistance 26 50 and also between the controller and the contact 37, and completing the circuits for the motor and the solenoid 38, the continued movement of the controller to the right gradually reducing the resistance in the 55 circuit with the motor and causing the motor to speed up gradually. In cutting out the motor to stop the car the controller 10 is shifted back to its initial position, thereby breaking the electrical connection between 60 the controller 10 and the resistance 26 and also between said controller and contact 37.

The elevator hatchway, as shown in Fig. 6, is provided with doors or gates, one door or one set of doors, of course, for each floor 65 which the elevator serves. In the preferred

form of the invention, mechanism is provided which, when the main hoisting motor is thrown out upon the arrival of the car at the floor at which the car is to stop, will operate automatically to open the door at 70 that floor. The door or set of doors at each floor and that part of the operating mechanism therefor which is individual to that floor are duplicates of the doors and the corresponding parts of the operating mechanism 75 for the other floors. In the present embodiment of the invention, the doors are all operated from a common operating or driving mechanism. The door driving mechanism is normally out of operation and is thrown into operation upon the cutting out of the main hoisting motor, and the doors are all normally disconnected from said driving mechanism. When the main hoisting motor is cut out with the car substantially at the floor at which it is to stop, the door driving mechanism is thrown into 80 operation and the door at that floor is connected with the door driving mechanism automatically. 85

As shown in Figs. 1, and, 3 to 6 inclusive, of the drawings, the hatchway is provided at each floor with two cooperating doors 68 and 70 of the well-known Peele type arranged to slide in suitable slides at the sides of the doorway. These doors are connected by cables 72 at the opposite ends of the doors, each attached at one end to the upper door 68, passing over a fixed pulley 74 and attached at its other end to a bracket 76 secured to the lower door 70. The doors may be evenly counter-balanced or the upper door 68 may be slightly heavier than the lower door so that the doors will always tend normally to close or to remain in closed positions. 90

The mechanism for operating the doors in the preferred form of the invention comprises two door operating lines 78, one for connection with each end of the lower door of each set at the respective floors. These door operating lines may consist of chains passing about sprockets 80 secured to a shaft 82 in the penthouse. This shaft, as shown, is arranged to be driven from a door motor 84 through a chain 86 passing about a sprocket on the motor shaft and a sprocket 88 on a shaft 82. The sprocket 88 is not secured rigidly to the shaft 82, but is connected with the shaft by means of a friction clutch comprising friction disks 90, one of which is secured rigidly to the shaft and the other of which is mounted to turn with the shaft but is movable longitudinally thereof and is held yieldingly in engagement with the sprocket by means of a coiled spring 91. This frictional connection between the door motor and the door operating shaft 82 constitutes a safety device preventing breakage of the parts of the door 100

mechanism in case the movement of the doors is obstructed or the door motor fails to stop at the proper time or some similar accident occurs, interfering with the proper operation of the door mechanism.

In the embodiment of the invention shown in Figs. 1 and 3 to 6 inclusive, the doors are operated by connecting the lower door with the door operating lines, while the lines are driven by the motor 84. The lower door is connected with the lines to open the doors by means of duplicate line clutches, one mounted on each end of the lower door. Each line clutch comprises a hook 92 secured to a rock shaft 94 mounted to turn in the bracket 76. The hook 92 is forked as shown in Fig. 5 so as to straddle the cable 78 and is arranged to engage a block or button 96 carried by said cable.

When the elevator is running normally, the hooks 92 at the several floors are held in retracted or inoperative position as shown in Fig. 1 and in full lines in Fig. 3. When the car arrives at or substantially at the floor at which it is to stop and the main hoisting motor is thrown off, the hook 92 on the door at that floor is thrown substantially into the position shown in dot-and-dash lines Fig. 3, and then will be engaged by the block 96 as the cable 78 is actuated in the direction indicated by the arrow, Fig. 3, and the lower door 70 at that floor will thereby be drawn downwardly and the corresponding upper door elevated. The hooks 92 on the doors at the other floors, however, will remain in their normal inoperative positions and will not be engaged by the blocks 96 at these floors. The lower door is moved upward positively to closed position by the reverse movement of the cable 78 through the engagement of the block 96 with the bracket 76 (see Figs. 3 and 4).

In the preferred form of the invention, locking devices are provided for locking the doors 68 and 70 in closed position, one locking device being arranged at each end of each set of doors. Each locking device comprises a locking member 98 pivoted at 100 on a bracket 101 secured to the side of the hatchway and having at its upper end projections or teeth arranged to engage a projection on a latch plate 102 secured to the upper door. The locking member 98 is connected with the clutch hook 92 so that said locking member is thrown into and out of locking position as the clutch hook is thrown respectively out of and into position to engage the block 96. To this end, the locking member carries at its lower end a pin 104 which is arranged to engage in a slot 106 in an arm 107 secured to the rock shaft 94. The locking member is acted upon by a compression spring 108 which tends to throw the same into locking position.

In the preferred form of the invention

illustrated, the line clutch and locking mechanisms are controlled in part from a cable 110, the upper end of which is attached to a lever 112 pivoted at 114 and the lower end of which carries a weight 116. The cable 110 carries a block 118 which is connected with the locking member 98 by means of duplicate links 120 forming one member of a toggle lever. The other member of the toggle lever consists of duplicate links 122 connecting the block with an actuating lever 124 pivoted at 126 on the bracket 101. The lever 124 has at its lower end a projection arranged to engage a contact plate 128 having inclined ends and secured to a bracket 130 attached to the side of the car 1.

The cable 110 is normally held in its elevated position and when in this position, the toggle lever 120-122 is broken; the locking member 98 is held in locking position, the hook 92 is retracted and the lever 124 is held out of the path of the contact plate 128. When the car arrives substantially at any one of the floors and the main hoisting motor is thrown out to stop the car at that floor, the cable 110 is allowed to descend to its lower position, thereby straightening the toggle lever 120-122 at that floor. The contact plate 128 is then engaged by the lever 124 at that floor, the locking member 98 is thrown out of action and the hook 92 is swung into operative position.

The cable 110 when it descends, operates to straighten the toggles 120-122 at all of the floors. Obviously, on account of the absence of a contact plate for engagement with the lever 124 at each of the floors except that at which the car is present, the straightening of the toggle has no effect on the locking members or clutch hooks 92 at these floors. Thus, the connection of the door with the door operating line is controlled by the car and is due to the presence of the car at the floor at which it is located when the hoisting motor is cut out.

When the doors reach the limit of their opening movement, the door motor is thrown out of operation and a brake is applied to the same to stop the movement of the doors. To close the doors, the operator depresses a push button which closes certain circuits, causing the door motor to be driven in reverse direction, thereby reversing the door operating line 78. During the reverse movement of the line, the blocks 96 engage the bracket 76 and lift the lower door, thereby closing the doors. When the doors are completely closed, the door motor is again thrown out and the brake is applied. As stated above the circuit for the solenoid 38 is broken when the main hoisting motor is thrown out of operation and during the opening and closing movement of the doors the parts of the toggle 120-122 and the parts connected therewith are held in the

position shown in dot and dash lines, Figure 3, by the weight 116. As the lower door is carried downwardly in opening the doors, each of the pins 104 is disengaged from the slot 106 in the corresponding arm 107. As the lower door is elevated in closing the doors, the pins 104 are again engaged in the slots 106. When the main hoisting motor is again thrown into operation, the cable 110 is lifted, thereby breaking the toggle 120—122, retracting the clutch hook 92 and the lever 124 to the positions shown in Fig. 3 and throwing the locking lever 98 into locking position at the floor at which the car has been stopped.

Figs. 7, 8 and 9 show a construction of line clutch and controlling mechanism which may be advantageously employed in connection with a single door arranged to slide upwardly to open and downwardly to close. The clutch mechanism shown in these figures comprises a clutch hook 130 similar to the hooks 92, but secured to the door indicated at 132 in a reversed position so that the hook is adapted to engage a block 134 secured to the cable 78. The hook 130 is secured to a rock shaft 136 mounted to turn in a bracket 138 secured to the door to which shaft is also secured a weighted arm 140. A third arm 142 secured to the rock shaft 136 is formed with a slot 144 in which engages a pin 146 mounted in the upper end of a locking lever 148 pivoted at 150 on a bracket 152 secured to the wall of the hatchway, the locking lever being arranged to engage a projection on a latch plate 153 secured to the door. In this construction as shown, the controlling cable 110 of the mechanism shown in Figs. 1 to 6 inclusive is eliminated, the line clutch and locking lever being respectively thrown into and out of operation by means carried by the car.

The hook 130 is normally held in retracted position and the locking lever 148 is normally held in locking position by a spring 154 mounted on a rod 156 and arranged to engage the lever 148. The hook is thrown into operating position and the locking lever is thrown out of locking position as shown in dot-and-dash lines Fig. 7 by means of a lever 158 pivoted at 160 on the bracket 152 and connected with the locking lever by a link 162. The lever 158 carries at its lower end a roll 164 arranged to engage the contact plate 128, on the car.

During the normal running of the car, the hook 130 and the locking lever 148 at each floor respectively are thrown into and out of operative positions as the car reaches a position adjacent each floor and after the car passes a floor, the hook and the locking member are restored to their normal positions by the spring 154. When the car is located at or substantially at a certain floor and the main hoisting motor is thrown out

to stop the car at that floor, the door operating line 78 is thrown into operation and is actuated in the direction of the arrow, Fig. 7, thereby elevating the door through the engagement of the block 134 with the hook 130. In closing the door, the door operating line 78 is reversed and the door is moved downwardly by the engagement of the block 134 with the bracket 138.

The door operating mechanism in the preferred form of the invention illustrated in the drawing, comprises the door operating motor 84, a brake 168 for controlling the motor and a motor brake solenoid 170 for controlling the action of the brake. When the solenoid 170 is energized, the brake is released and when the solenoid is deenergized, the brake is applied to the motor by a spring 171.

The direction in which the motor is driven is controlled by reversing switches 172 and 173, the latter when closed connecting circuits to drive the gate motor in the "opening" direction and the former when closed connecting circuits to drive the motor in the "closing" direction.

These switches may be closed by the energization of solenoids 174 and 175, respectively.

The solenoid 174 also operates a switch 176, and solenoid 173 also operates switches 177 and 178. An automatic relay or switch indicated as a whole at 179 operated by a solenoid 180 is provided, this solenoid controlling switches 181, 182 and 183.

In the present construction, mechanism is provided by which the doors, after they are started in operation, control their own operation. This mechanism in the present embodiment of the invention, comprises a chain or belt 184 passing about a sprocket secured to the shaft 82 and about a sprocket on a shaft 185 on which are mounted a series of cams. As the shaft 82 is rotated in a direction to open the doors, the shaft 185 is rotated in a clockwise direction, Fig. 1, and as the shaft 82 is rotated in a direction to close the doors, the shaft 185 is rotated in a counter clockwise direction. The shaft 185 and the cams mounted thereon constitute a selector or knock-out device which opens and closes various circuits hereafter to be described.

The reference number 186 indicates a commutator selector which is arranged to be driven through certain connections from the hoisting drum 4 and which makes and breaks certain of the electrical circuits at the proper time.

The solenoid 38 is arranged to actuate the levers 112 from which the cables 110 are suspended. In the illustrated construction, the levers 112 are attached to a rock shaft 187 to which shaft is also attached a lever 188 connected with the solenoid. The solenoid thus acts to lift and let fall the cables 110

in the manner above described. The sole- The circuit through the armature of the noid 38 also controls a switch 189 which is motor may be traced from the side 16 of the opened when the solenoid is energized and line through the wires 230 and 242, through is closed by the fall of the cables 110 when the resistance 244, the wires 246 and 247, is closed by the fall of the cables 110 when the resistance 244, the wires 246 and 247, the solenoid is deenergized.

The circuit connections for the door operating mechanism will be clearly understood by a reference to Fig. 16 of the drawings, 258, through the contacts 223 of the switch this diagram showing the condition of the parts when the car is running.

To understand the operation of the door line. A solenoid 260 is connected across the operating mechanism, let it be assumed that the car is running normally with all of the doors in closed positions, and that as the car arrives substantially at the floor at which it is desired to stop the car, the controller is adjusted that it does not pull in until the

10 is actuated to cut out the main hoisting counter E. M. F. of the motor has reached motor and to apply the brake to stop the car, approximately $\frac{2}{3}$ of its normal value. When

15 As the main hoisting motor 8 is thrown this E. M. F. is reached, the solenoid pulls out, the solenoid 38 is deenergized as above described.

20 The deenergization of this solenoid allows the cables 110 to fall, thereby throwing out the locking members 98 and 25

25 throwing the hooks 92 into position to engage the blocks 96 at the floor at which the car is located. The deenergization of the solenoid 38 also causes the closing of the sets of contacts 190 and 191 of the switch 189 which completes an initial circuit for the opening reversing switch 173.

30 The circuit which is thus formed starts from the point 192 at the side 16 of the main line, continues through the contacts 190 and 191, through the wire 193, across the commutator 186 to contact 194, then through wires 195, 196,

35 197, through contacts 198, 199 of switch 183, through wires 200, 201 and 202, through the magnet 175 of the reversing opening switch 173, then through the wire 204, across the

40 "open knock-out switch" 206, through wire 208, through the resistance 210, wire 212, 180 of relay 179, thence through wire 290,

45 through the stop button 216, wire 217, stop button 218 to key switch 220 and through wire 292 to point 223 on the other side of the line 18. When the opening reversing switch 173 has been energized as above explained, the contacts 223, 224 and 226 of said switch close. The closing of these contacts completes a circuit for the motor 84 and brake

50 solenoid 170, so that upon the closing of the switch 173, the motor brake is released, the motor commences to rotate and through the connections hereinbefore described drives the door or doors at the floor at which the car is stopped in an open direction.

55 The current through the brake solenoid may be traced from the point 229 on the lead 16, through the wires 230, 231 and 232, through the brake solenoid, thence through the wires 234 and 235, through the contacts 224 of the switch 173, thence through wire 236 to the contact 237 of the switch 172,

60 then through the wires 238 and 240 to point 241 on the other side of the line. The field circuit for the motor is indicated at

65 241, the current through the motor may be traced from the point 241 through the wires 239 and 242, through the contacts 223, 224 and 226 of switch 173, through the wires 230 and 231, through the contacts 223, 224 and 226 of switch 189, through the wires 234 and 235, through the contacts 224 of the switch 173, thence through wire 236 to the contact 237 of the switch 172,

70 then through the wires 238 and 240 to point 241 on the other side of the line. The field circuit for the motor is indicated at

75 241, the current through the motor may be traced from the point 241 through the wires 239 and 242, through the contacts 223, 224 and 226 of switch 173, through the wires 230 and 231, through the contacts 223, 224 and 226 of switch 189, through the wires 234 and 235, through the contacts 224 of the switch 173, thence through wire 236 to the contact 237 of the switch 172,

80 then through the wires 238 and 240 to point 241 on the other side of the line. The field circuit for the motor is indicated at

85 241, the current through the motor may be traced from the point 241 through the wires 239 and 242, through the contacts 223, 224 and 226 of switch 173, through the wires 230 and 231, through the contacts 223, 224 and 226 of switch 189, through the wires 234 and 235, through the contacts 224 of the switch 173, thence through wire 236 to the contact 237 of the switch 172,

90 then through the wires 238 and 240 to point 241 on the other side of the line. The field circuit for the motor is indicated at

95 241, the current through the motor may be traced from the point 241 through the wires 239 and 242, through the contacts 223, 224 and 226 of switch 173, through the wires 230 and 231, through the contacts 223, 224 and 226 of switch 189, through the wires 234 and 235, through the contacts 224 of the switch 173, thence through wire 236 to the contact 237 of the switch 172,

100 then through the wires 238 and 240 to point 241 on the other side of the line. The field circuit for the motor is indicated at

105 241, the current through the motor may be traced from the point 241 through the wires 239 and 242, through the contacts 223, 224 and 226 of switch 173, through the wires 230 and 231, through the contacts 223, 224 and 226 of switch 189, through the wires 234 and 235, through the contacts 224 of the switch 173, thence through wire 236 to the contact 237 of the switch 172,

305 the contacts 302 and 304 and through the wire 306 to the wire 301.

As soon as the solenoid 175 of the opening reversing switch 173 is energized as above explained, a set of holding contacts 308 and 310 forming part of switch 177 close and through the closing of these contacts the circuit of the solenoid is maintained after the contacts 198 and 199 are separated by the energization of the relay 179. The holding circuit for this solenoid is completed when the contacts 308 and 310 close and may be traced from the wire 196 through wires 280 and 311, through switch contacts 308 and 310, and wire 312, to wire 202, then through solenoid 175 to wire 204 and on as before. When the door has reached the limit of its opening movement, a cam 316 on the cam shaft 185 comes in contact with the knock-out switch 206, thereby actuating the switch to separate the switch contacts and breaking the circuit for solenoid 175 controlling the reversing switch 173. The breaking of the circuit for this solenoid causes the opening 20 of the switch, thereby throwing out the door operating motor and deenergizing the brake so that the brake is applied to the motor and the doors are brought to rest.

To close the door, one of the close push buttons 318 is pressed. Preferably there is one of these push buttons in the car and one at each floor outside of the hatchway. The depressing of this push button closes an initial circuit for energizing the solenoid 174 of the close reversing switch 172. The closing of this switch completes a circuit for the door motor 84 and brake solenoid 170, the motor is started in the reverse direction and the door commences to close, the starter solenoid 260 operating as before. The initial circuit whereby the close reversing switch is energized starts from the point 192 and continues through contacts 190 and 191, through wire 193, across commutator 186 to contact 194, through wires 195 and 320, across the push button 318, to wire 322, thence through wire 324, through the solenoid 174 of the reversing switch to wire 326, thence to knock-out switch 328. The contacts of this switch are closed when the door is open and therefore, the circuit continues through wire 330 and resistance 210 to wire 212, across stop button 216, wire 217, stop buttons 218, key switch 220 and through wire 222 to the side 18 of the line.

The energization of the reversing switch 172 closes the switch contacts 332, 237 and 334, which completes the circuits for the motor 84 and brake solenoid 170. The circuit for the brake solenoid may be traced from the point 229, through wires 230, 231 and 232, through the coil of the brake solenoid 170, through the wire 234, the switch contacts 237, wires 238 and 240 to the point 241 on the other side of the line. The cir-

cuit for the motor upon starting the motor may be traced from the point 229 on the line 16 through wires 230, 242, resistance 244, wire 246, switch contacts 332, wires 256, 254, through armature 252. From the armature, the circuit continues through wires 251, 250, 342, through switch contacts 334, contact 237, wires 238 and 240 to point 241 on the other side 18 of the line. The resistance 244 is short circuited in the same manner as before by the starter solenoid 260.

The close reversing switch 172 is provided with a set of holding contacts 344 and 346 forming part of switch 176 which shunt or short circuit the close push button 318 and thereby maintain the circuit of the close reversing switch 172 after the contacts of the push button separate. The circuit for the reversing switch when these holding contacts are closed and the contacts of the push button have separated, may be traced from the wire 195 through wires 196, 280, 348, through switch contacts 344 and 346 to wire 324, through solenoid 174, and on as before.

When the door is almost closed and preferably when it is within about an inch of full closure, a cam 350 on the cam shaft 185 comes in contact with knock-out switch 328 and actuates the switch to separate the switch contacts. The separation of the switch contacts opens the circuit of the close reversing switch, the switch opens the door motor is thrown out and the brake is applied to the motor so that the door is brought to rest.

The door may be stopped at any time during its opening or closing movement by pressing one of the stop buttons 216, 218.

When the controller 10 is actuated to start the car, the solenoid 38 is energized, thereby opening the switch contacts 190 and 191, and actuating the levers 112 to lift the cables 110. By the opening of the switch contacts 190 and 191, the circuit of the door opening relay 179, which remains closed after the closing of the reversing switch 175 until the car is started, is interrupted and the relay and switch contacts controlled thereby are restored to their normal positions. The mechanism is thus set for the next opening of the door. The lifting of the cables 110 throws the hooks 92 back out of operative position and swings the locking members 98 into locking position so that the door is locked when the elevator leaves the floor.

When all of the doors of the hatchway are closed, the knock-out switch 20 is held by a cam 352 on the cam shaft 185 in position to maintain the switch contacts closed. As soon as a door commences to open, the cam releases the knock-out switch and the switch opens, thereby opening the circuit for the main hoisting motor. When the door is closed, the cam 352 again engages the knock-out switch and closes its contacts. Thus it

7

is impossible to operate the car except when all of the doors are closed.

The door operating mechanism also preferably comprises a series of open push-buttons 354 by means of which an operator may cause the opening of the door at the floor at which the car is located. As shown in the diagram, there is one of these pushbuttons provided for the car and one for location at each floor on the outside of the hatchway. The circuits closed by the pressing of these open switches may be readily traced and need not be described in detail, the opening reversing switch of the door-operating 10 motor being operated in substantially the same manner as when the motor is thrown in automatically on stopping the car. The relay 179, however, is not affected by the closing of the circuit completed by depressing any one of these buttons.

It is to be understood that the invention is not limited to the particular form thereof illustrated and described in the present application, but that the invention may be embodied in other forms within the scope of the claims.

Having explained the nature of the object of the invention and having specifically described the mechanism embodying the invention in its preferred form, what is claimed is:

1. An elevator mechanism having in combination a hatchway, a series of doors for said hatchway, a car, car hoisting means, a door operating line for operating all of the doors thrown into operation automatically upon stopping the car in normal operation, and means controlled by the car for connecting the door at the floor at which the car is stopped with said line for movement with the line while the other doors are disconnected from the line.

2. An elevator mechanism having in combination a hatchway, a series of doors for said hatchway, a car, car hoisting means, a door operating line for operating all of the doors, and means thrown into operation automatically and only upon stopping the car in normal operation to connect the door at the floor at which the car is stopped with the door operating line positively for movement with the line while the other doors of the hatchway are disconnected from the line.

3. An elevator mechanism having in combination a hatchway, a series of doors for said hatchway, a car, car hoisting means, a door operating line for operating all of the doors, and means controlled by the car and thrown into operation automatically and only upon stopping the car to connect the door at the floor at which the car is stopped with the door operating line positively for movement with the line while the other

doors of the hatchway are disconnected 65 from the line.

4. An elevator mechanism having in combination a hatchway, a series of doors for said hatchway, a car, car hoisting means, a door operating line for operating all of the doors thrown into operation automatically upon stopping the car and means thrown into operation automatically and only upon stopping the car and operating to connect the door at the floor at which the car is 75 stopped with the door operating line positively for movement with the line while the other doors of the hatchway are disconnected from the line.

5. An elevator mechanism having in combination a hatchway, a series of doors for said hatchway, a car, car hoisting means, a door operating line for operating all of the doors thrown into operation automatically upon stopping the car and means controlled 80 by the car and thrown into operation automatically and only upon stopping the car and operating to connect the door at the floor at which the car is stopped positively with said line for movement with the line 90 while the other doors are disconnected from the line.

6. An elevator mechanism having in combination a hatchway, a series of doors for said hatchway, a car, car hoisting means, 95 means for operating the doors and means thrown into operation automatically upon stopping the car and means controlled by the car cooperating to cause the operation of the door at which the car is stopped while the 100 other doors remain closed.

7. An elevator mechanism having in combination a hatchway, a series of doors for said hatchway, a car, car hoisting means, a door operating line for operating all of the doors, line clutches for connecting the several doors with the door operating line and means thrown into operation automatically upon stopping the car in normal operation and means controlled by the car 105 cooperating to cause the clutching of the door at the floor at which the car is stopped to the line, while the other doors are unclutched from the line.

8. An elevator mechanism having in combination a hatchway, a series of doors for said hatchway, a car, car hoisting means, means for operating the doors, clutches for connecting the doors with the door operating means, means thrown into operation 115 automatically upon stopping the car for actuating said clutches, comprising a cable connected with the several clutches, a weight attached to the cable, means for raising and lowering the cable and a contact plate carried by the car, said last means and contact plate cooperating to cause the engagement of the clutch for the door at the floor at 125

which the car is stopped while the other clutches are disengaged.

9. An elevator mechanism having in combination a hatchway, a series of doors for said hatchway, a car, car hoisting means, a door operating line for operating all of the doors thrown into operation automatically upon stopping the car in normal operation, a clutch member carried by said line at each floor, a clutch member connected with each door for engagement with the corresponding clutch member on the line to connect the door positively with the line and means carried by the car for causing the actuation of the clutch member connected with the door at the floor at which the car is stopped with the corresponding clutch member on the line, while the clutch members connected with the other doors are held in their inoperative positions.

10. An elevator mechanism having in combination a hatchway, a series of doors for said hatchway, a car, car hoisting means, a door operating line, a clutch member carried by the line at each floor, a clutch member connected with each door for engagement with the corresponding clutch member on the line, common means thrown into operation upon stopping the car in normal operation for actuating all of the clutch members connected with the several doors to carry the same into position to engage the corresponding clutch members on the line and means carried by the car cooperating with said last means to cause the movement of the clutch member connected with the door at the floor at which the car is stopped into position to engage the corresponding clutch member on the line while the clutch members connected with the other doors are held in their normal inoperative positions.

11. An elevator mechanism having in combination a hatchway, a series of doors for said hatchway, a car, car hoisting means, devices for controlling the car hoisting means, means to start and stop the car, means for operating all of said doors arranged to be thrown into operation automatically when the car is stopped in normal operation and normally disconnected therefrom, and means controlled by the car for connecting the door at the floor at which the car is stopped with the door operating means while the other doors are disconnected from said means.

12. An elevator mechanism having in combination a hatchway, a series of doors for said hatchway, a car, car hoisting means, means for controlling the hoisting means to start and stop the car, means for operating the doors normally disconnected from the doors, normally inactive means adapted to cause the connection of any one of the doors with said operating means, means for throwing said last means into op-

eration and means controlled by the car for rendering said last means effective to connect the door at the floor at which the car is stopped with said door operating means while the other doors are disconnected from said means.

13. An elevator mechanism having in combination a hatchway, a series of doors for said hatchway, a car, car hoisting means, means for controlling the hoisting means to start and stop the car, means common to all of the doors for operating all of the doors, normally inactive means common to the several doors adapted to cause the connection of any one of said doors with said operating means, means for throwing said last means into operation and means controlled by the car for rendering said last means effective to connect the door at the floor at which the car is stopped with said door operating means while the other doors are disconnected from said means.

14. An elevator mechanism having in combination a hatchway, a series of doors for said hatchway, a car, car hoisting means, means for controlling the hoisting means to start and stop the car, means common to the several doors and thrown into operation automatically upon stopping normally the car for operating all of the doors, means common to the several doors, thrown into operation automatically upon stopping the car and adapted to cause the connection of any one of the doors with said operating means, and means controlled by the car for rendering said last means effective to connect the door at the floor at which the car is stopped with said operating means while the other doors are disconnected from said means.

15. An elevator mechanism having in combination a hatchway, a series of doors for said hatchway, a car, car hoisting means, means for controlling the hoisting means to start and stop the car, means for operating the doors, a single electro-magnetic device, means controlled by said electro-magnetic device and means controlled by the car cooperating to cause the opening of the door at the floor at which the car is stopped while the other doors remain closed.

16. An elevator mechanism having in combination a hatchway, a series of doors for said hatchway, a car, car hoisting means, means for controlling the hoisting means to start and stop the car, means for operating the doors, and means comprising a single electro-magnetic device only for causing the opening of the door at the floor at which the car is stopped while the other doors remain closed.

17. An elevator mechanism having in combination a hatchway, a series of doors for said hatchway, a car, car hoisting means, means for controlling the hoisting means to

- start and stop the car, means for operating the doors and means comprising a single electro-magnetic device only operating automatically when the controlling means is actuated to stop the car for causing the opening of the door at which the car is stopped while the other doors remain closed.
18. An elevator mechanism having in combination a hatchway, a series of doors for said hatchway, a car, car hoisting means, a door operating line for operating all of the doors, frictionally acting means for actuating said line, means for connecting any one of the doors positively with said line, and means controlled by the movement of a door for controlling the line actuating means.
19. An elevator mechanism having in combination a hatchway, a series of doors for said hatchway, a car, car hoisting means, common means for operating all of the doors, a friction drive for the door operating means, means for connecting the several doors with said operating means and disconnecting the same therefrom and means controlled by the movement of a door for controlling the door operating means.
20. An elevator mechanism having in combination a hatchway, a series of doors for said hatchway, a car, car hoisting means, means for controlling the hoisting means to start and stop the car, means for operating the doors, a single electro-magnetic device, means controlled by said device and thrown into operation upon stopping the car, and means controlled by the car cooperating to cause the doors to remain closed during the normal running of the car and to cause the opening of the door at a floor at which the car is stopped while the other doors remain closed.
21. An elevator mechanism having in combination a hatchway, a door for said hatchway, a car, car hoisting means, means for controlling the hoisting means to start and stop the car, means for operating the door, a clutch for connecting the door with said operating means, a solenoid, mechanism for operating the clutch, a connection between the solenoid and said mechanism, a contact plate carried by the car arranged to be engaged by said mechanism and cooperating with the solenoid to cause said clutch to be maintained out of operation when the main hoisting mechanism is in operation and when the car is remote from a floor and to throw the clutch into operation when the main hoisting mechanism is thrown out of operation and the car is at or adjacent a floor.
22. An elevator mechanism having in combination a hatchway, a door for said hatchway, a car, car hoisting means, means for operating the door, and means thrown into operation automatically upon stopping the car, and means controlled by the position of the car cooperating to cause the operation of said door when the car is stopped at or adjacent the floor at which said door is located.
23. An elevator mechanism having in combination a hatchway, a door for said hatchway, a door operating line, a car, car hoisting means, two interengageable line clutch members, one carried by the line and one connected with the door for connecting the door positively with the line for movement with the line, and means thrown into and out of operation automatically upon stopping and starting the car, and means controlled by the position of the car cooperating to move one of said clutch members into and out of position to engage the other clutch member.
24. An elevator mechanism having in combination, a hatchway, a series of doors for said hatchway, a car, car hoisting means, common means for operating the doors, a clutch at each floor for connecting the doors respectively with the door operating means, a solenoid, mechanisms for throwing the several clutches into and out of operation, a connection between the solenoid and said mechanisms, a contact plate carried by the car arranged to be engaged by said mechanisms and cooperating with the solenoid to cause the clutches to be maintained out of operation when the main hoisting mechanism is in operation and when the car is remote from a floor and to throw the clutch into operation when the main hoisting mechanism is thrown off and the car is at or adjacent said floor.
25. An elevator mechanism having in combination a hatchway, a door for said hatchway, a car, car hoisting means, a door operating line, a clutch hook for connecting the door directly with said line, a solenoid, means for throwing the clutch hook into and out of operation, a connection between the solenoid and said mechanism, a contact plate carried by the car arranged to be engaged by said mechanism and cooperating with the solenoid to cause the clutch hook to be maintained out of clutching position with relation to the line when the main hoisting means is in operation and when the car is remote from a floor and to throw the clutch hook into operation when the main hoisting means is thrown out of operation and the car is at or adjacent a floor.
26. An elevator mechanism having in combination a hatchway, a door for said hatchway, a car, car hoisting means, a door operating line, a clutch hook for connecting the door directly with the line, mechanism comprising a toggle for operating the clutch hook, a solenoid, a connection between the solenoid and the central joint of the toggle for controlling the position of the toggle, a contact plate mounted on the car, and a lever connected with the toggle and arranged to

engage the contact plate to control the position of the clutch hook through the toggle.

27. In combination a hatchway, floor landings and gates along said hatchway at the several floors, a car and car hoisting means, a hand controller therefor, gate operating mechanism comprising a movable member at each of said floors, a contact member on the car and means comprising an electromagnetic device common to all the gates and arranged to cooperate with said contact member to actuate the movable member upon moving the said controller to neutral position.
- 15 28. In combination a hatchway, floor landings and gates along said hatchway, a car and car hoisting means, a hand controller for said hoisting means, means for moving the several gates and devices cooperating to cause said gate opening means to open a gate at one of said floors upon moving said controller to neutral position, comprising a contact member on the car, a movable member at the floor and an electromagnetic device common to all the gates and controlled from said controller.

29. In combination with an elevator car, a hoisting motor, a circuit therefor, a hand controller, gates at the several floors, gate operating means, an electrically controlled 30 device for controlling the gate operating means, a circuit for said device and switches for said circuits operated by said controller to break both said circuits upon moving the controller to neutral position. 35

30. In combination, a hatchway, floor landings and gates, a car and car hoisting means, a hand controller, gate operating means, a cam and lever for controlling said gate operating means, an electromagnetic device for relatively actuating said cam and lever, a circuit for said hoisting means, a circuit for said electromagnetic device, and means for opening both of said circuits upon the moving of said hand controller to its 40 45 neutral position.

Signed at Hoboken, New Jersey, this 5th day of October 1921.
